UNITED STATES PATENT OFFICE

2,508,831

MUSICAL TOY

Samuel V. Lippman, Hartford, Conn.

Application May 6, 1947, Serial No. 746,198

4 Claims. (Cl. 46—174)

1

This invention relates to novel ways and means whereby a user may trap and compress air and forcibly project air streams or jets from the means into his mouth in a manner to produce musical tones which, when harmoniously rated and timed, make it possible to "play" any desired tunes, the wanted results being attainable by specially manipulating the mouth without humming, whistling or blowing.

Ordinarily, when a person sings, hums, whistles or blows on a horn or into a simple resonator such as a jug or the like, the needed air is drawn into the lungs, for explosive use, by way of the nostrils, mouth or both. However, using one's mouth or oral cavity as a sort of resonator for sound waves emanating from without is not new, as shown, for example, in Patent No. 931,578 of August 17, 1909, to S. R. Divine. Then, too, novel performances have been given where the performer, by rhythmically clapping the concaved sides of cupped hands together, "pumps" air jets into his oral cavity which are then transformed into music making tone waves. In an effort to carry the exterior hand pumping principle forward, I contrived a mechanical means to more efficiently "scoop" in and better compress the air. In accordance with my original concept, I adopted a structural assemblage characterized by an appropriate base which was proportioned and otherwise made and shaped to rest against the chest of the user, the base being provided at its transverse end portions with hand grips to rest against the butt portions of the palms of the hands of the user. By attaching a standard to the central portion of the base and causing same to rise vertically, the standard was employable as a suitable body to accommodate marginally arranged padding or cushioning means. By properly shaping the cushioning means and causing opposite surface portions to project beyond corresponding surfaces of the body, air-trapping chambers were thus provided on both sides of the body. Then, by employing two levers, crossing the levers and pivotally mounting same at corresponding ends on the standard, said levers served suitably to accommodate hand-grips at their lower ends and to carry concavo-convex, shell-like lids or covers at their upper ends. The covers had their concave sides disposed opposite the air chambers and were such in size as to function as air-trapping and compressing shells or members. Objectionable impact and noise was reduced by bringing the marginal edge portions of the shells into silent contact with the cushioned surfaces of the padding. Therefore,

2

a structure of the type stated is the subject matter of my copending application, Serial No. 686,051, filed July 25, 1946.

In order to make the structure less cumbersome, to materially reduce the weight and to allow same to be employed more readily by youngsters, certain new and useful improvements and refinements were adopted and these constitute the principal subject matter of the instant application. Therefore, it is an object of the present invention to provide two units of concavo-convex form which are adapted to be fitted into the respective hands of the user and held on the hands by straps or bands which encircle the hands. At least one unit has a concavo-convex side defining an air chamber and this air chamber is surrounded by a marginal cushion with a discharge orifice for the projected air jets or streams. The remaining unit, which traps and compresses the surrounding air, is provided with a concavo-convex diaphragm with the convex side opposed to and adapted to telescope into the concavity or air chamber so as to forcibly expel the compressed air through the outlet in the form of jets, the latter being projected into the oral cavity of the user's mouth in the manner stated for purposes of producing musical sounds.

Other objects and advantages will become more readily apparent from the following description and the accompanying illustrative drawings.

In the drawings:

Figure 1 is a view illustrating the manner in which the instrument is utilized;

Figure 2 is a face view of the cupped unit;

Figure 3 is a back view of the co-operating unit; and

Figure 4 is a vertical sectional view through both units illustrating in detail the construction thereof.

Referring to the drawings in detail, a cupped unit or member designated generally 10 comprises a rigid substantially concavo-convex body or shell 11 provided with a peripheral flange 12. The body 11 forms an air chamber 13 in which air trapped between it and a complementary unit is compressed as the two units are moved rapidly, or at any predetermined tempo or rate, toward one another.

Attached to the flange 12 on the concaved side 50 of said body 11 is a suitable cushion 14 preferably composed of a sponge rubber body 15 encased in a soft pliable covering 16 such as chamois skin or the like. Enclosing the convex side of body 11 is a fabric casing 17 and extending transversely across the body is a finger strap 18 which is

adapted to embrace the fingers of the hands of the user.

Co-operating with unit 10 is a second complementary cover unit designated generally 19 which comprises a cupped body 20 of concavo-convex shape which corresponds in size and shape to the body 11 and is provided with an outstanding peripheral flange 21 which corresponds to the flange 12.

The convex side of the body 20 is encased in a suitable fabric covering 22, and fixed adjacent opposite sides of the body 20 on its convex side is a finger embracing strap 23.

The cushion 15 and its covering 16 are provided near the upper end of the vibrator 10 with a groove 24 forming a constricted passage through which air trapped in the chamber 13 by the advance of units 10 and 19 toward one another will be compressed and forcibly expelled and projected in the form of air streams or jets.

Obviously, the device so far described may be utilized for the purpose of compressing air in the chamber and expelling it forcibly through the constricted passage formed by the groove 24, so that the air stream issuing from the passage may be suitably aimed and directed into the mouth of the user and by altering the size and shape of the oral cavity, sounds of varying pitch may be produced.

In order to render the device more effective I find it advantageous to provide a convexed diaphragm member 25 which is provided with a peripheral flange 26. The member 25 conforms in all respects to the size and shape of the cupped bodies 11 and 20 but is attached to the flange 21 of the member 20 in any suitable manner so that the flanges 21 and 26 lie contiguous with one another. A cushion designated generally 27 overlies the flange 26 and like the cushion 14 comprises a body 28 of sponge rubber or the like encased in a flexible covering 29 of chamois skin or the like.

When the device employing the convex member 25 is used it will be obvious that the cushions 14 and 28 will be brought into contact with one another as the units are advanced toward one another, and will serve to restrict the distance that the convex member 25 may enter into the chamber 13. At the same time the displacement of the air in the chamber 13 by the approach of the companion units will be materially increased so that the same volume of air expelled through the constricted passage 24 in the cushion 14 will likewise be increased without requiring the expenditure of any appreciable increased amount of energy.

In use, the two units 10 and 19 are fastened on the left and right hands of the user by way of the straps 23 and 18 so that the convexed outward surfaces of said units are thus strapped into the cupped hands. Obviously, by moving the hands toward and from each other according to requirements of a predetermined tempo and in keeping with the rhythmic pattern in mind, surrounding air is picked up, trapped, and compressed between the convexed diaphragm member 25 and the surfaces defining the stated air chamber 13. The thus compressed air is expelled in jet-like streams, which latter are potential tone waves. Upon entering the oral cavity of the open mouth of the user, as illustrated in a general way in Fig. 1, it will be evident that the air streams or waves are transformed into

sound or tone waves within the confines of the stated mouth. Then, and according to the skill of maneuverability of the mouth by the performer, he is able, using my "hand pump," to make music in a novel fashion.

While in the foregoing there has been shown and described the preferred embodiment of this invention it is to be understood that minor changes in the details of construction, combination and arrangement of parts may be resorted to without departing from the spirit and scope of the invention as claimed.

Having described my invention, what I claim as new is:

1. An air-trapping, compressing and air expelling device for projecting and directing air streams into a user's open mouth comprising, in combination, a unit in the form of a hand-sized concavo-convex body, said body having a marginally arranged restricted air discharge orifice, and an air-trapping cover unit including a compressing and expelling member of such a size and shape that its marginal edge portions make air-tight contact with corresponding marginal edge portions of said body when superposed upon the concave side thereof so as to cause said cover unit to lid over and forcibly expel from the body through said orifice air trapped by the engagement of the two units.

2. The structure specified in claim 1, together with air tight cushioning means secured to and substantially surrounding the marginal edge portion of said body.

3. The structure specified in claim 1, wherein said member is of convex form, the convex surface thereof being of size and configuration to telescope closely into the concaved side of said body.

4. An air-trapping, compressing and expelling hand pump for producing manually pressured air jets timed to conform to given rhythmic patterns comprising a concavo-convex shell-like body adapted to fit with its convexed side into the cupped palm of one hand of the user, cushioned padding attached to and marginally surrounding the concave side of said shell and adjoined to the shell in substantially air-tight relationship, said padding being provided at a predetermined point with a restricted air stream discharge orifice, a second concavo-convex shell member adapted to be fitted into the cupped palm of the user's other hand, said latter member constituting a cover for the open concaved side of the first-named member and being of a shape and size to permit its marginal edge portions to come into air-tight contact with the major portions of said padding, and a convexed diaphragm fitted into the concaved side of said second-named member, said diaphragm being of a size and shape to telescope into the concaved side of said first-named member to trap, compress and expel air through said discharge orifice.

SAMUEL V. LIPPMAN.
